(57) **CLAIM**

The ornamental design for a pedalboard for a musical instrument, as shown and described.

DESCRIPTION

FIG. 1 is a front perspective view of the pedalboard for a musical instrument showing my design.

FIG. 2 is a front elevation view thereof;

FIG. 3 is a back elevation view thereof;

FIG. 4 is a side elevation view thereof;

FIG. 5 is an opposite side elevation view thereof;

FIG. 6 is a top plan view thereof;

FIG. 7 is another upper perspective view, showing a second embodiment with six slots;

FIG. 8 is another upper perspective view, showing the third embodiment with eight slots;

FIG. 9 is another upper perspective view, showing a third embodiment with eight slots with unclaimed environment; and,

FIG. 10 is another upper perspective view, showing the first embodiment with unclaimed environment.

The side views in all embodiments are the same. The front and back views are similar in all embodiments, only changing in length according to the number of slots.

The broken line showing of parts of the drawings is included for the purpose of illustrating environment and forms no part of the claimed design.
